United States Patent Office.

SETH W. PERKINS, OF GENESEO, ILLINOIS.

Letters Patent No. 68,528, dated September 3, 1867.

IMPROVED WIRE SNAP-HOOK.

The Schedule referred to in these Letters Patent and making part of the same.

TO ALL WHOM IT MAY CONCERN:

Be it known that I, SETH W. PERKINS, of Genesco, in the county of Henry, and State of Illinois, have invented a new and improved Combined Snap-Hook and Buckle; and I do hereby declare that the following is a full, clear, and exact description thereof, which will enable others skilled in the art to make and use the same, reference being had to the accompanying drawings, forming part of this specification, in which—

Figure 1 is a view of my improved snap-hook and buckle attached to a strap.

Figure 2 is a perspective view of the same detached from the strap.

Similar letters of reference indicate like parts.

My invention has for its object to furnish an improved combined snap-hook and buckle, simple in construction, strong and durable, easily attached and detached, and which can be manufactured at a comparatively small expense; and it consists in the construction of the snap-hook, and in the combination therewith of a single or double buckle tongue, the whole being constructed and arranged as hereinafter more fully described.

A is the snap-hook, which is formed of a single piece of wire, the middle part of which is flattened and bent around upon itself, as shown in figs. 1 and 2, to form the ring or loop a^1 for the attachment of the strap. The ends of the wire are twisted so as to make a quarter turn around each other, and are then flattened and bent into hooks, which overlap and lie along each other, as shown in fig. 2, a groove being formed between the hooks at the end of the snap for convenience in attaching it to a ring. B is the buckle-tongue, which is clasped or bent around the inner coil of the loop a^1 , and its longer end rests upon the outer coil or coils of said loop, as shown in fig. 2, and its shorter end projects as shown.

In attaching the strap it is first put over the longer arm of the tongue, and drawn up to the base of said arm. The other end or arm of the tongue is then passed through the strap, the end of which is passed through the keeper, after which the strap is brought back to its proper place upon the longer arm of the said tongue. If desired, a single or ordinary tongue may be used, but I prefer the double tongue, as herein described, as being less liable to tear out of the strap. This enables the snap-hook to be used as a buckle to attach it to the strap at the same time that it is used as a snap-hook and attached to a ring. By slightly modifying the form of the loop a^1 the snap-hook may be used as a snap cock-eye for all the purposes to which a cock-eye is ordinarily applied.

Having thus described my invention, what I claim as new, and desire to secure by Letters Patent, is—

An improved snap-hook, formed of a single piece of wire bent into substantially the form shown and described, that is to say, with a ring loop, a^1 , to receive the strap, and with its hooked ends a^2 overlapping each other, in combination with the single or double buckle tongue, as and for the purpose set forth.

SETH W. PERKINS.
